UNITED STATES PATENT OFFICE.

GEORGE FLEURY DE GROOT AND IRA LYNN THOMPSON, OF MORRISTOWN, NEW JERSEY, ASSIGNEES OF ONE-THIRD TO PATRICK FARRELLY, OF NEW YORK, N. Y.

COLLECTION-RECORDING MECHANISM.

SPECIFICATION forming part of Letters Patent No. 700,019, dated May 13, 1902.

Application filed August 8, 1901. Serial No. 71,355. (No model.)

To all whom it may concern:

Be it known that we, GEORGE FLEURY DE GROOT and IRA LYNN THOMPSON, citizens of the United States, and residents of Morris-
5 town, in the county of Morris and State of New Jersey, have invented a new and Improved Collection-Recording Mechanism, of which the following is a full, clear, and exact de-
scription.

10 This invention relates to improvements in mechanism for recording at a post-office or other central station the collection of mail-
matter from the street or deposit boxes; and the object is to provide a mechanism for
15 this purpose electrically controlled, operating upon the opening of a letter-box to record on a strip of paper the number of the collector, the number of the box, and the date and hour of collection, thus indicating whether collec-
20 tions are promptly made; and a further object is to provide an electrically-controlled device or devices for locking and releasing the letter-box door at stated intervals.

We will describe a collection - recording
25 mechanism embodying our invention and then point out the novel features in the ap-
pended claims.

Reference is to be had to the accompanying drawings, forming a part of this specification,
30 in which similar characters of reference indicate corresponding parts in all the figures.

Figure 1 is a sectional elevation of a recording apparatus embodying our invention and its connection with a current-controller on a
35 letter-box. Fig. 2 is a sectional view through the apparatus and showing a shifting and strip-feeding mechanism employed. Fig. 3 is a section on the line 3 3 of Fig. 2. Fig. 4 is a plan view of the printing mechanism. Fig.
40 5 is a section on the line 5 5 of Fig. 4. Fig. 6 is a section on the line 6 6 of Fig. 5. Fig. 7 is a side elevation of a circuit-controller em-
ployed. Fig. 8 is an edge view thereof. Fig. 9 shows a box-door locking and releasing mech-
45 anism employed, and Fig. 10 is a section on the line 10 10 of Fig. 9.

It may be here stated that a recording de-
vice will be provided in the office in connec-
tion with the several letter-boxes over which
50 a collector of mail has control—that is, the

several letter-boxes in a route will be connect-
ed in series with the apparatus. Therefore a
recording apparatus will be required for each
collector. However, as they are all of similar
construction an illustration and description 55
of one will answer for all.

Arranged within the casing 20 at the post-
office is the recording mechanism, comprising
a tens-wheel 21, mounted on a shaft 22, and a
units-wheel 23, mounted on a shaft 24. These 60
wheels are designed for printing the number
of the letter-box from which letters are being
removed. These wheels 21 and 23 are sup-
ported on a base 25, and also supported on
this base is an hour-wheel 26, having print-
65 ing-figures on its periphery to indicate the
hours of the day. This hour-wheel is mounted
on a shaft 27, and at the side of the hour-
wheel is a minute-wheel 28, which is mounted
on a shaft 29, designed to be connected, 70
through the medium of a coupling 30, with the
minute-hand arbor of a clock mechanism. On
the shaft 29 is a disk 31, provided with a sin-
gle tooth 32, designed upon each rotation to
75 engage with one of the teeth of a gear-wheel
33, mounted on a shaft 34. This gear-wheel
33 has twenty-four teeth, or one for each hour
of the day. On the shaft 34 is also secured
a gear-wheel 35, meshing with a gear-wheel
80 36 on the shaft 27 of the hour-wheel 26. By
this arrangement it is obvious that the min-
ute-wheel will be operated continuously with
the clock mechanism. At the end of sixty
85 minutes, however, the tooth 32 of the disk 31
will engage with a tooth of the gear 33 and
through the medium of the gears 35 and 36
will rotate the hour-wheel one step or to
bring the next hour-type into printing posi-
tion.

On a shaft 37 is a printing-wheel 38 for in-
dicating the day of the month—that is, it has
printing characters on its periphery from "1"
to "31." On this shaft 37 is a gear-wheel 38^a,
designed to be engaged by a tooth 39 on a
disk 40, attached to the shaft 34. This disk 90
40 will have a complete rotation every twenty-
four hours, and at the end of each twenty-
four hours or at midnight the tooth 39 will
engage with a tooth of the gear 38^a, impart-
ing a single step motion to the day-printing 95
100

disk 38 to bring the printing character of that day of the month in printing position.

On the shaft 41 is mounted a printing-disk 42 for printing the number of the collector 5 operating in connection with this recording mechanism, and also mounted on this shaft 41 is a printing-wheel 43 for printing on a strip of paper the month of the year. These printing-wheels 42 and 43 are designed to be 10 manually rotated on the shaft to bring the proper printing characters into position, and when adjusted they may be held by means of a set-nut 44.

Connected to the shaft 22 of the printing-wheel 21 is a ratchet-wheel 45, and connected to the shaft 24 for the printing-wheel 23 is a ratchet-wheel 46. These ratchet-wheels are 15 designed to be engaged by escapements 47 47^a to operate first the tens-wheel and then the 20 units-wheel, as will be hereinafter described. The escapements 47 47^a are mounted on posts, which form bearings for the shafts. Mounted to slide on a stirrup 48 is a tappet 48^a. This stirrup is attached to a link 49, the upper end 25 of said link being attached to a lever 50, upon which is an armature 51, coacting with an electromagnet 52. This electromagnet is designed for raising the stirrup and tappet, while they are lowered by means of a spring 53, connecting at one end with the armature-lever and at the other end with a fixed portion of the casing. A lateral sliding movement of the tappet is caused by an armature-lever 54, pivoted at 55 and having an armature 56 coacting with an electromagnet 57.

A strip of paper 58 is fed from a roller 59, mounted on the casing, and passes downward into the casing around an idler 60, and thence 40 underneath the printing-rollers to a feeding device hereinafter described.

Underneath the printing-rollers for the box-number and for the time-printing wheels is a vertically-operating platen 61, and operating vertically underneath the other printing-wheels is a vertically-moving platen 62. A 45 rod 63 extends downward from the platen 61 through guides 64 and 65 and is designed to be engaged by a hammer 66 on a lever 67, which is operated by engagement therewith 50 of a lug 68, loosely mounted on a disk 69, mounted on a shaft 70, said shaft being kept in constant rotation by a suitable motor, which it is deemed unnecessary to show herein.

At one side of the disk 69 is a clutch-section 55 71, designed to be engaged by a swinging clutch-section 72. This clutch-section 72 is so connected to the shaft 70 as to rotate therewith, but has a longitudinal movement thereon, and as a means for moving the clutch-section 72 into engagement with the clutch-section 71 the said section 72 is mounted to 60 rotate in a lever 73, pivoted to the lower portion of the casing and connected at its upper end with an armature 74, coacting with an electromagnet 75. When the electromagnet 75 is energized, as will be hereinafter described, it will attract the armature 74 and

by rocking the lever 73 engage the clutch-section 72 with the clutch-section 71, causing the disk 69 to rotate and by bringing the lug 70 68 into contact with the end of the lever 67 will move the hammer 66 upward, forcing it against the end of the rod 63, which will cause the platen 61 to press the paper against the printing-wheels. 75

After the printing operation above described the strip of paper is to be moved one step to provide a new space for the next printing operation. This paper-feeding mechanism consists of a block 76, mounted to slide 80 on a rod 77 and held yieldingly by a spring 78. Pivotally connected to the lower side of the block 76 is a gripping-dog 79, designed to engage the under side of the paper and to press it closely against the block 76. An operating-rod 80 has pivotal connection with said gripping-dog 79 and has bearings in studs 81. Between one of the studs 81 and a collar 82 on the rod is a spring 83. At the free end of the rod 80 is an upwardly-extended finger 84, designed to be engaged by the lug 68 on the disk 69. Therefore after this lug 68 passes the lever 67 and engages with the finger 84 it will draw the rod 80 rearward against the tension of its spring 81, causing 95 the dog 79 to release its hold on the paper, and thus permit the said dog and block 76 to move rearward. Then as the lug 68 releases the finger 84 the spring 83 will cause an opposite movement of the rod 80, so that the 100 dog 79 will grip the paper and cause it, with the block, to move along one step.

The platen 62 has link connection 85 86 with pins 87 88, the inner ends of which move in a fixed sleeve 89 and are pressed apart by 105 a spring, as clearly indicated in Fig. 3. The outer ends of these pins 87 88 are engaged, respectively, with face-cams 90 and 91, mounted on a shaft 92, on which is mounted a pulley 93, engaged by a band 94, which passes 110 around a pulley 95, loosely mounted on the shaft 70, these pulleys 93 and 95 being of equal diameter, so that a complete rotation of the pulley 95 will cause a complete rotation of the pulley 93. The pulley 95 is provided with a clutch-section 96, designed to be engaged by a clutch-section 97, mounted to rotate with the shaft 70, but having a longitudinal movement thereon. This clutch-section 97 is carried by a lever 98, pivoted at 115 its lower end and connecting at its upper end with an armature 99, coacting with an electromagnet 100. As before stated, the shaft 70 is in constant rotation. Therefore when the magnet 100 is energized and attracts the 120 armature 99 the said shaft will be put in clutch connection with the pulley 95, and therefore the pulley 93 will be rotated, so that the face-cams 90 and 91 will force the pins 87 and 88 inward, swinging the links 85 125 and 86 to cause an upward movement of the platen 62, forcing the paper against the printing-wheels, and thus printing the collector's 130 number, the month, and the day.

The band 94 also passes around a pulley 101, mounted on a shaft 102. This pulley 101 is loosely mounted on the shaft, and a spring 103 is connected at one end to said pulley, 5 while the other end is connected to the shaft. Also mounted on the shaft 102 is a pinion engaging with a gear-wheel 104, on the shaft of which is a stop-disk 105, having a notch in its periphery adapted to be engaged by a stop- 10 pin 106, carried on the lower end of a lever 107. The upper end of said lever is designed to be engaged by a tappet 108 on the shaft 92. Therefore during the movement of the band 94 the pulley 101 will be turned in such direction as to wind the spring 103, the shaft being held by the stop-wheel 105, engaged by the finger 106. When, however, the tappet 108 engages with the upper end of the lever 107, it will move the finger 106 out of engagement with the stop-disk, permitting the spring 103 to cause a reverse movement of the shaft 102, and a finger 109 on said shaft 102 will engage with a shoulder 110 on the rod 80, moving said rod against the resistance of its 20 spring 83, and when the finger 109 shall have passed said shoulder 110 the rod will be released, so that its spring 103 will move it forward and cause a feeding movement of the paper strip, as before described. Of course 25 during the rotation of the stop-disk 105 the end of the finger 106 will ride upon its periphery until the notch in the disk comes in line with the finger, when a spring 111, attached to the lever 107, will move the finger 30 into said notch, thus stopping the movement of the parts.

We will now describe the means for closing the electric circuit upon the opening of a letter-box. Attached to each letter-box is a casing 112, within which a controller-disk 113 is mounted to rotate. From a sprocket-wheel 114 on the shaft of this controller-disk a sprocket chain or strap 115 extends to a connection with a sprocket-wheel 116, mounted 45 in an offset 117 of the casing 112, and the shaft 118 for this sprocket-wheel 116 has connection with the pintle of the hinge for the door 119. The sprocket-pinion 114 instead of being rigidly attached to the shaft of the 50 disk 113 is connected to a barrel 120, within which is a winding-spring 121, this spring 121 being connected at one end to the barrel and at the other end to the shaft of said controlling-disk. The shaft 118 has a clutch connection with the sprocket 116, so that said sprocket will be rotated only when the door 55 is opened. As the door is closed, however, the sprocket-wheel 116 must remain still, permitting the spring 121 to rotate the disk 113. 60 For this purpose we have shown a clutch-section 122 between said shaft 118 and the sprocket-wheel 116. The movement of the disk 113 is governed as to its speed by means of a balance-wheel 123, within which is a balance-spring 124. It may be here stated that 65 the speed of the disk 113 should be about one turn in three seconds. A gear-wheel 125 on

the shaft of the disk 113 engages with an intermediate gear 126, which engages with a pinion 127, on the shaft of which is a ratchet-wheel 128, with which engages a pawl 129. On the shaft of the disk 113 is a disk 130, having a notch 131, in which a finger 132 on a brake-lever 133 is designed to engage. This brake-lever is pivoted at its lower end, and its upper end is designed to engage with the balance-wheel 123 to stop the same after the disk 113 shall have made one complete revolution and the finger 132 drops back into the notch 131. It will be seen that one wall of 80 the notch or the wall opposite the direction of rotation of the disk is cam-shaped or curved, so as to cause the finger to ride outward toward the periphery, where it is held until the finger again reaches the notch, as before 85 described. The rotation of the disk 113 is designed to move the wheels 21 or 23 to indicate the box-number. It is provided in its periphery at intervals with blocks of insulating material. As here shown, short blocks of insulating material are indicated by the numerals 1 2 3 4, the longer strip or block by the numeral 5, then three short blocks numbered from 0 to 2, and then a strip numbered 3, of insulating material, is considerably longer 90 than the strip numbered 5. A contact-pin 134 has spring-yielding contact with the periphery of the disk 113. From this pin 134 a wire 135 leads to one pole of a battery 136, and from the other pole of this battery a wire 100 137 leads to a binding-post 138, which has connection with one end of the coil of an electromagnet 139, the object of which will be hereinafter described, and from the other end of this electromagnet 139 a wire 140 extends to 105 the electromagnet 52, and from this electromagnet 52 a wire 141 leads to a binding-post 142, from which a wire 143 leads to electrical connection with the disk 113. Coacting with one pole of the electromagnet 52 is an armature 144, and as this armature 144 is designed 110 to have a slower movement than the armature 51 we connect said armature 144 or its lever with a piston-rod 145, operating in a dash-pot 146. This armature 144 has electrical connection with a binding-post 147, from 115 which a wire 148 leads to the electromagnet 57, and from this electromagnet 57 a wire 149 leads to a binding-post 150, having connection with the wire 137, and the opposite end 120 of said electromagnet is designed to close the circuit for energizing the electromagnet 57 by engaging with a contact-screw 151, from which a wire 152 leads to the pole of the battery 136 opposite that engaged by the wire 137. It 125 will be understood that the current is normally closed through the electromagnets 52 and 139. The electromagnet 139 is designed to control the closing of the circuit through the electromagnet 75. As here shown one 130 end of the electromagnet 75 is connected by wire 153 with a binding-post 154, from which a wire 155 extends to the wire 148, and from the other end of the electromagnet 75 a wire

156 leads to a binding-post 157, having wire connection with the armature-lever 158, co-acting with the electromagnet 139. This armature-lever 158 is regulated in its opening movement, or rather it is caused to have a slow opening movement by means of a dash-pot 159. When in this open position, the armature-lever 153 comes in contact with a contact-point 160, from which a wire 161 leads to 10 a connection with the wire 137.

We will now describe a means for locking a street letter-box during the time that mails are not to be collected, the said means being so arranged as to automatically release the 15 box during hours of collection. This locking means is shown clearly in Figs. 9 and 10. Attached to the inner side of the box-door 119 is a keeper 162, designed to be engaged by the hook end of a swinging latch 163, pivoted to a wall of the box. This latch 163 also forms an armature for the electromagnet 164, arranged in the box. This electromagnet is connected by wires 165 and 166 to the main line-wires, the wire 165 being practically a 20 continuation of the main wire 152, while the wire 166 is a continuation of the wire 143. As here shown, the current is to be closed between the wire 166 and the main wire through a contact-point 167, designed to be engaged 25 by a lever 168, which is connected to the line-wire by a wire 143. A disk 170 is rotated by a clock mechanism or other means, and on this disk and extending about one-half its circumference is a cam portion 171. When 30 said cam portion comes in contact with the end of the lever 168, it forces it down upon the contact-point 167 and closes the circuit through the electromagnet, thus drawing the latch 163 out of engagement with the keeper 35 162, so that the door 119 may be opened during the hours of collection. When the line-wires are open, however, at the end of the day's collection, the electromagnet 164 will be de-energized, permitting the locking-latch 40 to fall into engagement with the keeper.

The general operation of the device is as follows: When the collector opens the door of the letter-box, the shaft 118 will be revolved, winding the spring 121, as before described. Upon closing the door said spring 45 will cause a single rotation of the controlling-disk 113. The insulating-blocks in the periphery of the disk are designed to indicate the box-number. When the disk begins to revolve, it will first open the circuit, which 50 will permit the armature 50 to fall and allow the escapement 47 to pass one tooth of its ratchet-wheel, which will bring the "1" of the tens-wheel 21 in place to print; but as 55 this is not the number of the box the strip of insulating material (numbered 1 in Fig. 7) is very short and will open the circuit for a 60 very short time, and when the contact-point 134 is reached midway between the first and 65 second insulating-blocks the circuit will be again closed, allowing the escapement-wheel to move once more, which sets the type-wheel

half-way between "1" and "2," and when the circuit is opened by the contact-point 134 coming in contact with the second rubber 70 strip it will permit the escapement to tick once again, turning the "2" in position to print, and so on until the first figure or tenths of the number of the box comes in connection with the insulating-block numbered 75 5 in Fig. 7. This strip or block is made very much longer than the others and causes the circuit to stay open long enough to permit the armature 144 to come in contact with the point 151. As before stated, the dash-pot 146 will cause a slow movement of said 80 armature. When this contact is made, the local circuit is closed through 147 and 150 and through the magnet 57, which, drawing upon the armature 56, moves the part 48^a 85 from the escapement 47 and engages it with the escapement 47^a, which operates the units printing-wheel. When the disk 113 moves sufficiently or to the point marked 0 in Fig. 7, the circuit is opened, permitting the armature 50 to fall, causing the units type-wheel to turn in position for "1" to print, and so on to the figure which is to be printed on the number of the box, as before described. Then when the contact-point 134 engages with the 90 long block numbered 3 in Fig. 7 the circuit will be held open sufficiently long to permit the armature 158 to come in contact with the point 160. The dash-pot permits this movement in about one second. This causes the 95 circuit through the electromagnet 75, which throws the friction-clutch section, as before described, causing the feed of the paper and also causing the platen to rise. This platen rises, however, before the paper strip is fed 105 along.

Having thus described our invention, we claim as new and desire to secure by Letters Patent—

1. In a collection - recording mechanism, a recording device located at a central office, an electric circuit in which the recording device is located, a circuit-controller supported on a letter-box for opening and closing the electric circuit and means in the circuit for unlocking the box, substantially as specified.

2. In a collection-recording mechanism, a recording device located at a post-office, electric devices for causing movements of the recording devices, an electric circuit in which the electric devices are placed, and a circuit-controller supported on a letter-box and operated by a movement of the letter-box door, substantially as specified.

3. In a collection-recording device, a recording mechanism, comprising printing-wheels, electric devices for causing movements of said printing-wheels, for printing on a record-strip, electric devices for controlling the feeding of said record-strip, an electric circuit in which said electric devices are located, and a circuit-controller supported on a letter-box and operated by a movement of the letter-box door, substantially as specified.

4. In a device for recording the collection of mail-matter, a recording mechanism adapted to be located at a central office and comprising printing-wheels, platens movable relatively to said printing-wheels, an electromagnet for causing the movements of said printing-wheels to print the number of the box from which the collection is made, means for imparting motion to others of the printing-wheels, electric devices for moving the platens, electric devices for causing the feeding movement of a record-strip, an electric circuit in which said electric devices are arranged, and a circuit-closer located on a letter-box and operated by an opening movement of the letter-box door, substantially as specified. 70
5. In a collection-recording mechanism, a recording device, comprising printing-wheels for printing on a strip the number of a letter-box, printing-wheels for printing the time of the collection from said letter-box, said last-named printing-wheels being adapted for connection with a clock mechanism, an electric device for operating the first-named wheels, means for causing a step-by-step movement of a paper strip, platens for moving the paper against the printing-wheels, electric devices for controlling the movements of said platens, an electric circuit in which the electric devices are arranged, and a circuit-controller in the circuit and attached to the letter-box, the said circuit-controller being operated by a movement of the letter-box door, substantially as specified. 75
6. In an apparatus for recording the collection of mail-matter, a recording mechanism located at a post-office, said recording mechanism comprising printing-wheels, for printing on a record-strip movable along said wheels, platens movable under the printing-wheels, means for moving the printing-wheels to printing position, means for moving the platens toward the printing-wheels when in such printing position, means for feeding the strip after the printing, electric devices for controlling the movements of said printing-wheels, platens and paper strip, an electric circuit in which said electric devices are arranged, and a circuit-closer in the circuit and arranged on a letter-box, the said circuit-closer being operated by a movement of the letter-box door, substantially as specified. 80
7. In a collection-recording mechanism, a recording apparatus, comprising printing-wheels, an electric circuit, electric devices in said circuit for causing movements of certain of the printing-wheels, a circuit-closer operated by a letter-box door for closing and opening said circuit, a record-strip-feeding device, comprising a sliding block, a gripping-dog pivoted to said block, a rod extended from said dog, a spring for moving the rod in one direction, a rotating shaft, a disk loosely mounted on said shaft and having a lug, electrically-controlled means for locking said disk to the shaft, causing said lug to engage with said rod and move it in one direction, and a platen also operated by said lug, substantially as specified. 85
8. In a collection-recording mechanism, a recording apparatus located at a post-office or the like, electric devices for operating the printing apparatus, an electric circuit in which said electric devices are located, and a circuit-closer comprising a casing attached to a letter-box, a disk mounted in said casing and having blocks of insulating material spaced apart, a contact-point engaging with the periphery of said disk, said contact-point being arranged in the electric circuit, a spring for rotating said disk, and means actuated by an opening movement of the letter-box door for winding said spring, substantially as specified. 90
9. A mail-collection-recording mechanism, comprising a recording device arranged at a central station, electrically-controlled means for causing movements of the recording apparatus, an electric circuit in which said electrically-controlled means are located, a circuit-closer, comprising a casing adapted to be secured to a letter-box, a disk mounted to rotate in said casing and having insulating-blocks spaced apart in its periphery, a contact-pin engaging with the periphery of said disk, a spring for causing a movement of said disk in one direction, a connection between said spring and the pintle of the box-door hinge, whereby the spring will be wound upon opening the door, a governor for the spring, and a brake for the disk, substantially as specified. 95
10. In a mail-collection-recording mechanism, two printing-wheels for printing the number of a letter-box from which mail is collected, ratchet-wheels mounted on the shafts of said printing-wheels, escapements for engaging with said ratchet-wheels, a tappet adapted for engagement with either one of said escapements, an electromagnet for causing the movement of said tappet from one escapement to the other, an electromagnet for moving the said tappet out of engagement with the escapement, a spring for moving the tappet into engagement with said escapement, an electric circuit in which the said electromagnets are located, and a circuit-controller in the circuit, said circuit-controller being attached to a letter-box and operated by an opening movement of the letter-box door, substantially as specified. 105
11. In a recording mechanism, a recording device, an electric circuit in which the recording device is located, a circuit-closer arranged in a box having a door, a spring for operating said circuit-closer in circuit-closing direction, and connections between said spring and the box-door whereby the spring is wound by opening movement of the door, substantially as specified. 110
12. In a recording apparatus, printing-

wheels, means for causing the movements of said printing-wheels, a platen movable under certain of said printing-wheels, an electromagnet for causing an operative movement 5 of said platen, an electromagnet for controlling the circuit through the first-named electromagnet, an electric circuit, and a circuit-controller located on a letter-box and operated by a movement of the letter-box door, substantially as specified.

13. In a recording mechanism, a recording device, an electric circuit in which the recording device is located, a letter-box having a door, a circuit-closer in the box and operated 15 by a movement of the door, a lock for the door, and devices arranged in the electric circuit for releasing said lock, substantially as specified.

14. In a recording mechanism, a recording

device arranged at a central station, an electric circuit in which the recording device is placed, a letter-box, a circuit-closer in said letter-box, a swinging latch for locking the door of the box, an electromagnet for moving said latch in one direction, the said electromagnet being arranged in the said electric circuit, and a device in the circuit for closing the same and energizing said electromagnet, substantially as specified.

In testimony whereof we have signed our 30 names to this specification in the presence of two subscribing witnesses.

GEORGE FLEURY DE GROOT.
IRA LYNN THOMPSON.
